United States Patent Office

Des. 185,367
Patented June 2, 1959

185,367

APRON

Bess Kaye, New York, N.Y.

Application February 16, 1959, Serial No. 54,635

Term of patent 14 years

(Cl. D3—26)

Fig. 1 is a front elevational view of an apron, showing my new design; and

Fig. 2 is a rear elevational view thereof.

I claim:

The ornamental design for an apron, substantially as shown.
